(57) **CLAIM**

I claim the ornamental design for a vape pen, as shown and described.

DESCRIPTION

FIG. 1 is perspective view of a vape pen in accordance with the principles of the present disclosure;

FIG. 2 is front elevational view of the vape pen of FIG. 1;

FIG. 3 is a rear elevational view of the vape pen of FIG. 1;

FIG. 4 is right side view of the vape pen of FIG. 1;

FIG. 5 is a left side view of the vape pen of FIG. 1;

FIG. 6 is a top plan view of the vape pen of FIG. 1; and,

FIG. 7 is a bottom plan view of the vape pen of FIG. 1.

The broken lines in the drawing views show portions of the vape pen that form no part of the claimed design.
